UNITED STATES PATENT OFFICE.

JOSEPH J. KWIS, OF FINDLAY, OHIO, ASSIGNOR TO ADAMS BROTHERS COMPANY, OF FINDLAY, OHIO.

POWER DEVICE FOR PUMPING WELLS.

SPECIFICATION forming part of Letters Patent No. 712,314, dated October 28, 1902.

Application filed June 5, 1902. Serial No. 110,320. (No model.)

To all whom it may concern:

Be it known that I, JOSEPH J. KWIS, a citizen of the United States, and a resident of Findlay, in the county of Hancock and State 5 of Ohio, have invented a new and useful Improvement in Power Devices for Pumping Wells, of which the following is a full, clear, and exact description.

This invention relates to improvements in 10 power devices for pumping wells of the class disclosed in United States Letters Patent No. 591,283, issued to me on October 5, 1897, although the present improvements may be used on other types of machines.

15 The object of the present invention is to provide simple and substantial means for holding a vertical spindle in a perfectly rigid condition in the framework of a power device for pumping wells, thereby effectually 20 overcoming all liability of the power-wheel assuming a tilted or canted position.

With these ends in view the invention consists in the combination, construction, and arrangement of parts, which will be herein- 25 after fully described and claimed.

Reference is to be had to the accompanying drawings, forming a part of this specification, in which similar characters of reference indicate corresponding parts in all the figures.

30 Figure 1 is a vertical sectional elevation through a spindle-supporting means embodying the present invention, the plane of the section being indicated by the dotted line 11 of Fig. 2. Fig. 2 is a plan view of the de- 35 vices shown by Fig. 1. Fig. 3 is a detail perspective view of the spindle removed from its supporting devices, and Fig. 4 is a detail perspective view of the foot-block adapted to engage with the lower extremity of said spindle.

40 The foundation for supporting the driving mechanism of the power device for pumping wells is similar to the devices in common use, and a portion of this foundation is shown by Figs. 1 and 2 of the drawings. A series of 45 mudsills 5 support the parallel main sills 6, the latter being gained into the mudsills and secured firmly thereto by the bolts 7 and the keys 8. These main sills are provided with transverse gains or recesses, (indicated by 50 dotted lines at 9 in Fig. 1,) and on the main sills are mounted the parallel pony-sills 10,

the latter being arranged at right angles to the main sills and substantially parallel to the mudsills, although said pony-sills are raised somewhat above the mudsills, as shown 55 by Fig. 1. These pony-sills are rabbeted, as indicated at 11 in Fig. 1, and the reduced ends of the pony-sills are fitted in the gained or recessed portion 9 of the main sills. One of the pony-sills is secured by a plurality of 60 bolts 12 to the main sills, while the other pony-sill is fastened solidly to the main sills by the bolts 13 and the keys or wedges 14, as shown by Fig. 2. The pony-sills are disposed in parallel relation and separated a short dis- 65 tance from each other in order to accommodate the vertical stationary spindle 15, the latter being made in one piece with a polygonal or angular portion 16 and having its lower portion extended or prolonged a suit- 70 able distance, as at 17, below said angular or polygonal portion. (See Fig. 3.)

The pony-sills are provided on their opposing faces with the angular recesses 18 18^a, which are disposed in registration and form 75 a socket or opening adapted to receive the angular or polygonal section 16 of said spindle, and said pony-sills are drawn or clamped tightly upon said polygonal section of the spindle by means of the bolts 19, the latter 80 passing through the pony-sills on opposite sides of the opening or passage formed by the coincident recesses 18 18^a. (See Fig. 2.)

The spindle 15 is preferably made of the tapering or conical form shown more clearly 85 by Figs. 1 and 3, and between this conical spindle and the angular portion 16 thereof is arranged a rib or shoulder 20, the latter being adapted to rest on the top edges of the pony-sills 10 and serving to limit the endwise 90 displacement of the spindle in a downward direction. The spindle is fitted and clamped between the pony-sills at a point intermediate of its length, so that the conical part of said spindle will extend above the pony-sills 95 for a suitable distance to receive the sleeve 21 and the power-wheel 22. This sleeve is provided at its lower portion with an annular flange 23, which is arranged to rest upon the shoulder 20 of the spindle, and said sleeve is 100 provided with an interior tapering bore which conforms to the taper of the conical part 15

of the spindle, while on its outer surface said sleeve is provided with a cylindrical bearing-face 24, which conforms to the diameter of the opening in the hub of the power-wheel 22.

5 25 designates a cross-sill which is disposed below the pony-sills between adjacent mud-sills and is adapted to rest against the under side of the main sills 6. I employ the single cross-sill 25, which extends in the same general direction as the pony-sills and which is adapted to lie in the vertical plane of the space between said pony-sills. This cross-sill is secured firmly to the main sills by means of certain of the bolts 12 13, that fasten the pony-sills to the main sills, and said cross-sill is provided with a single vertical opening adapted to receive the lower extended portion 17 of the spindle. (See Fig. 1.)

The spindle is provided with a longitudinal passage 26, which extends through the conical bearing portion 15, the angular portion 16, and the extended lower extremity 17, the end portions of said passage opening through the upper and lower extremities of said spindle. The lower extremity of the extended portion 17 of this spindle is prolonged through the cross-sill 25, and said end of the spindle is fitted snugly in a foot-block 27, the same being shown more clearly by Figs. 1 and 4. 30 This foot-block is cast in a single piece of metal and in the chambered form shown by the drawings, and the upper portion of the foot-block is provided with an annular flange 28, from the face of which projects a series of studs or teeth 29. The lower end of the foot-block is provided with a perforation, which is disposed in the vertical plane of the passage 26 through the spindle, and said foot-block is fitted to the cross-sill 25, so as to have 35 the toothed face of its flange 28 bear against the lower edge of said cross-sill.

30 designates a tie-rod which extends entirely through the spindle and the foot-block, said tie-rod serving to bind the spindle and 45 the foot-block to the parts of the foundation-frame and to draw the foot-block so tightly against the cross-sill that the teeth 29 will be embedded in said sill. The upper end of the tie-rod is provided with a head or nut 31, 50 which is adapted to bear upon the plate or shoulder 32, the latter resting upon the upper end of the spindle 15. The sleeve is not clamped tight on the spindle, but is loose to turn freely thereon. The lower end of said 55 tie-rod is screw-threaded for the application of a nut 33, that is adapted to bear against

the under side of the foot-block 27, and this tie-rod and its nut not only draw the spindle in a downward direction, but they exert upward pressure on the foot-block. 60

The means herein described for securing the spindle in the framework serves to hold the spindle in a perfectly rigid position, and this result is secured largely by the employment of the prolonged portion 17 of the spindle fitting in the cross-sill and in the foot-block, the latter being held in the under side of the cross-sill by the same vertical tie-rod that primarily holds the vertical spindle against displacement within the pony and 70 cross sills.

Having thus described my invention, I claim as new and desire to secure by Letters Patent—

1. In an apparatus of the class described, 75 the combination with a cross-sill and pony-sills, of a spindle clamped in the pony-sills and having an extended portion which is carried downwardly through the cross-sill, a foot-block engaging with said prolonged end of 80 the spindle, and means for clamping the spindle and the foot-block to said sill.

2. In an apparatus of the class described, the combination with pony-sills and a cross-sill, of a spindle having a polygonal section 85 clamped in the pony-sills, and a prolonged portion which is carried through said cross-sill, a foot-block clamped to said cross-sill and engaging said extended portion of the spindle, and a bolt passing through the spindle and the foot-block. 90

3. In an apparatus of the class described, the combination with pony-sills and a cross-sill, of a spindle having a polygonal portion clamped in the pony-sills, and an extended 95 portion which is carried through said cross-sill, a foot-block having a toothed face engaging with the cross-sill and also arranged to receive the lower extremity of said extended portion of the spindle, and a tie-rod passing 100 through said spindle and the foot-block, said rod having means for clamping said foot-block against the cross-sill and causing the teeth thereof to become embedded in said sill.

In testimony whereof I have signed my 105 name to this specification in the presence of two subscribing witnesses.

JOSEPH J. KWIS.
